UNITED STATES PATENT OFFICE.

HENRY K. COWEN, OF CHICAGO, ILLINOIS, ASSIGNOR TO INTERNATIONAL HARVESTER COMPANY, A CORPORATION OF NEW JERSEY.

GAS-PRODUCER.

No. 841,123.

Specification of Letters Patent.

Patented Jan. 15, 1907.

Application filed May 7, 1906. Serial No. 315,651.

To all whom it may concern:

Be it known that I, HENRY K. COWEN, a citizen of the United States, residing at Chicago, in the county of Cook and State of Illinois, have invented certain new and useful improvements in Gas-Producers, of which the following is a specification, reference being had to the accompanying drawings, forming a part thereof.

10 My invention relates to gas-producers, and is particularly applicable to that type commonly called "suction-producers," in which the flow of air to the retort to aid combustion is induced by the suction operation of an explosive-engine in drawing in charges of gas through conduits communicating with the retort. It is the common practice in this class of producers to subject the gases to a cleaning and purifying process between their exit 15 from the retort and their admission to the engine-cylinder to remove elements injurious to the operation of the engine. These elements consist, in part, of combustible matter that has not been submitted to sufficient heat to properly remove it; and the object 20 of my invention is to provide a mechanism that will secure a more perfect combustion and consequent removal of such matter from the gas prior to its exit from the retort.

25 In the accompanying drawings, illustrating my invention, Figure 1 represents a gas-producer embodying my invention. Fig. 2 is a sectional elevation of the retort. Fig. 3 is a cross-section of Fig. 2 on line A B, and Fig. 4 is a cross-section of Fig. 2 on line C D.

The same reference-numerals represent the same parts throughout the several views.

30 1 represents a retort; 2, a scrubber; 3, an explosive-engine; 4, a pressure-tank having a pipe connection with the exhaust-opening in the cylinder of the engine; 5, a vaporizer receiving heat from a gas-conduit 6, communicating with the retort and scrubber; 7, an air-conduit communicating with the vaporizer and the retort; 8, an air-inlet adapted to admit air to said vaporizer; 9, a gas-conduit leading from the scrubber to the engine; 10, a relief-pipe connected with the gas-conduit 6 and having a valve 11 to control its communication therewith.

35 12 is a feed-water cup adapted to receive water from a source of supply by means of a pipe 13 and from which it is conducted to the vaporizer.

14 represents the base of the retort, which 55 may be provided with any of the common forms of ash-receivers and grates.

15 is a cylindrical shell within the outer shell of the retort and forming an air-chamber 15', extending upward along the wall of 60 the retort and adapted to receive air from the vaporizer through the conduit 7, and 16 represents a refractory lining extending inward from said shell and forming a fire-pot 17, that extends a short distance above the 65 air-chamber 15'. Projecting upward from the wall of the fire-pot are a series of short columns 18, upon which rests a refractory lining for the upper portion of the shell of the retort. The inner surface of the lining inclines inward and downward and forms a fuel-magazine 19, having a flaring mouth portion to receive the fuel from the charger, and a contracted neck portion through which the fuel passes to the fire-pot. The upper portion of the retort between the upper end of the magazine 19 and the charger is conical 70 and connects with a common form of charging mechanism 20, having a depending cylindrical portion 21 to direct the fuel to the 80 receiving-chamber 19.

The upper end of the refractory lining of the fire-pot inclines upward and outward and the lower end of the lining of the magazine 19 inward and downward, and the short 85 columns are arranged in a manner to form a downwardly and inwardly inclined intervening gas-chamber 22 between the two linings with which the gas-conduit 6 communicates.

Leading from the upper conical chamber of 90 the retort is a pipe 23, having a regulating-valve 24, and the pipe extends downward along the outside of the retort and communicates with the lower end of the air-chamber 15'. A pipe 25 connects the upper end of the 95 pipe 23 with the pressure-tank 4.

In operating the producer the retort is provided with fuel, and when the fuel has reached a stage of combustion causing that portion below the plane of the gas-chamber 100 22 to become sufficiently incandescent to produce a proper form of gas the valve 11, connected with the relief-pipe, is closed and the engine started. The suction of the engine induces a current of air into the producer and 105 a flow of gas therefrom. The fuel in the magazine above the gas-chamber is not heated to a sufficient degree to render it incan-

descent; but there is sufficient heat developed to form gas having impure elements, and it has been found desirable to prevent, so far as possible, the mixture of this gas with 5 that flowing to the engine, the latter being the primary object of my invention.

The pipe 23, connecting the upper part of the retort with the lower part of the air-chamber, is designed to conduct the impure 10 gases downward to said chamber in a manner to have them pass through the zone of incandescence in the fire-pot to relieve them of their combustible matter; and a downward current in said pipe is induced by the entrance 15 therein of exhaust-gases from the engine by means of the pipe 25, connected with the pressure-tank, and such current may be regulated by means of the valve 26.

What I claim, and desire to secure by Letters Patent, is—

1. A gas-producer comprising, in combination, a retort, said retort comprising a fire-pot, an air-chamber communicating with said fire-pot, a fuel-magazine adapted to deliver fuel to said fire-pot, a chamber above 25 said magazine, a pipe connecting said upper chamber and said air-chamber, an explosive-engine connected with said gas-producer, said engine having an exhaust-port and a 30 pipe connection between said exhaust-port and said pipe connecting the upper chamber of the retort with said air-chamber, whereby a downward flow of gas is induced through said pipe connection from said upper chamber.

2. A gas-producer comprising, in combination, a retort, said retort comprising a fire-pot, an air-chamber communicating with said fire-pot, a fuel-magazine adapted to deliver fuel to said fire-pot, a chamber above 40 said magazine, a pipe connecting said upper chamber and said air-chamber, an explosive-engine connected with said gas-producer, said engine having an exhaust-port, a pipe connection between said exhaust-port and 45 said pipe connecting the upper chamber of the retort with said air-chamber, whereby a downward flow of gas is induced through said pipe from said upper chamber, and means for controlling said flow of gas.

3. A gas-producer comprising, in combination, a retort, said retort comprising a fire-pot, an air-chamber communicating with said fire-pot, a fuel-magazine adapted to deliver fuel to said fire-pot, a chamber above 55 said magazine, a pipe connecting said upper chamber and said air-chamber, an explosive-engine connected with said gas-producer, said engine having an exhaust-port, a pressure-tank, a pipe connection between said 60 pressure-tank and said exhaust-port and between said pressure-tank and said pipe connecting the upper chamber of the retort with said air-chamber, whereby a downward flow of gas is induced through said pipe from said 65 upper chamber.

HENRY K. COWEN.
